UNITED STATES PATENT OFFICE.

JAMES T. WETHERALD, OF BOSTON, MASSACHUSETTS.

DESIGN FOR A SYRINGE-NOZZLE.

SPECIFICATION forming part of Design No. 28,861, dated June 14, 1898.

Application filed February 14, 1898. Serial No. 670,333. Term of patent 14 years.

To all whom it may concern:

Be it known that I, JAMES T. WETHERALD, of Boston, county of Suffolk, and State of Massachusetts, have invented and produced 5 a new and original Design for a Syringe-Nozzle, of which the following is a specification, reference being had to the accompanying drawings, forming a part thereof.

Figure 1 shows in front elevation a syringe-10 nozzle embodying this invention; Fig. 2, a side elevation of the same; Fig. 3, a plan view of the same.

As shown in the drawings, the leading or 15 material features of my syringe-nozzle consist in a body egg shape in horizontal cross-section, having its sides curved and gradually decreasing in circumference from the base to the tip, said tip being turned to one side,

rounded, and provided with perforations near its end and the curved sides provided with an 20 elongated recess just below the tip.

a is the body of my syringe-nozzle, *b* the perforations in the tip near its end, and *c* the elongated recess in the curved sides just below the tip. 25

I claim—

The design for a syringe-nozzle, as herein shown and described.

In testimony whereof I have signed my name to this specification in the presence of 30 two subscribing witnesses.

JAMES T. WETHERALD.

Witnesses:

H. B. DAVIS,
B. J. NOYES.
